PACKAGING MACHINE

George L. McCargar, Detroit, Mich.

Application July 15, 1946, Serial No. 683,735

4 Claims. (Cl. 249—19)

1

The present invention relates to a packaging machine, and is primarily concerned with a novel, practically operative machine for rapidly packaging food materials, one example of which is spinach in substantially exact amounts as to weight, and in a compressed condition so as to greatly reduce the space occupied in comparison to the space filled by the same weight loose spinach occupies. With the machine of my invention, the material to be packaged, in practice in bags, is rapidly conveyed by a conveyor to the machine, and at the delivery end of the machine, in a compressed condition, is contained within bags, the weights of spinach within the bags being substantially the same and with such tolerances as are legally required with respect to the representation of the weights of materials which are publicly sold in packages. With the machine of my invention, and as one object and purpose thereof, very rapid packaging of the normally loose and bulky materials which the machine is to handle is attained by means of a machine which occupies relatively small space and in which gravity is utilized in part, together with electrical controlling circuits and compressed air or other equivalent compressive fluid for operating movable parts of the machine in proper timed relation to each other, for a continuous, speedy and substantially perfect handling and packaging of the type of food materials mentioned.

An understanding of the invention may be had from the following description, taken in connection with the accompanying drawings in which,

Fig. 1 is a vertical section, with parts shown in side elevation, of a machine made in accordance with my invention, the section being from front to rear.

Fig. 2 is a transverse vertical section through the upper portion of the machine.

Fig. 3 is a horizontal section therethrough.

Fig. 4 is a fragmentary side elevation of the collecting and weighing drum mechanism, and the mechanism used for its operation and control.

Fig. 5 is a fragmentary rear elevation of one of the safe guarding controls of the machine.

Fig. 6 is a horizontal section through the machine, at a lower plane than in Fig. 3, showing the compressor mechanism in plan.

Fig. 7 is a front elevation thereof somewhat enlarged.

Fig. 8 is a fragmentary under plan view illustrating the releasable bag holding mechanism at its operative position.

2

Fig. 9 is a similar under plan enlarged, showing the bag holding mechanism released.

Fig. 10 is a fragmentary vertical section showing, in side elevation, the bag holding mechanism, and

Fig. 11 illustrates diagrammatically the electrical and pressure fluid control circuits and mechanisms of the machine.

Like reference characters refer to like parts in the different figures of the drawings.

The supporting frame structure of the machine includes vertical front and rear posts 1 at four corners of the machine (Fig. 6), the side posts being connected by side bars 2 in any number required extending between said posts, and with transverse bars 3 between the front and rear posts, making a light, rigid supporting frame.

At the upper end of the frame, horizontal rods 4 are located and mounted above the upper side frame bars 2, upon which an inclined gate support, having spaced sides 5 and an upper horizontal bar 6 connecting them at their upper ends, is located. At the inner sides of the side bars 5, longitudinal grooves 7 are cut for slidably receiving and guiding the vertical edge portions of the gate 8 which, in form as shown, is of rectangular outline. The gate support with the gate thereon is mounted for adjustment lengthwise of the rods 4 by means of blocks 9 slidable on said rods, and as shown in Fig. 2. The gate with its support may be adjusted as to its angle of inclination to the vertical, manually operated screws being used to release the gate frame and the blocks 9 for adjustment, the tightening of the screws securing the gate in any position to which it may be adjusted.

The gate is movable lengthwise of the groove 7. Lever 10 (Fig. 2), pivotally mounted between its ends on one side 5 of the gate carrying frame, at one end, is longitudinally slotted. A pin or screw 11 passes through the slot and connects with the gate 8 so that movement of the lever 10 about its pivot moves said gate in accordance with the direction of movement of the lever. Links 12 are interposed between said lever and the lower end of a piston rod 13, said links being pivotally connected at their ends thereto. The piston rod connects with a piston within a vertical cylinder 14 mounted on the same side member 5 and adapted, as hereafter described, to have a pressure fluid, such as compressed air, carried into the cylinder alternately at opposite ends thereof. The movement of the piston in opposite directions reciprocates the gate 8.

There is also mounted on the rods 4 a depending vertical stop 15 disposed toward the front

upper end portion of the machine, having a curved arcuate section 15a at its lower end. Said stop plate 15 is secured to members 16 which may be adjusted lengthwise of the rods 4. Side plates 17 extend rearwardly from the vertical edges of the plate 15 and similarly spaced side plates 18 (Fig. 1) extend rearwardly from the sides 5 of the gate frame. An endless conveyor 19 is located around a roller 20 at its front mounted at the rear upper portion of the supporting frame. Said conveyor is driven at a desired speed with the upper run of the belt moving in the direction indicated by the arrows in Fig. 1, so that the material, such as stalks or leaves of spinach, or other similar vegetables at 10 21, are projected in a forward direction and strike against the stop plate at 15 thereafter dropping downwardly by gravity. Such projection of the material 21 to the full extent shown in Fig. 1 must be with the gate 8 elevated. When the gate is lowered, the spinach leaves or other materials strike against it and drop downward by gravity at a different place in the machine.

A drum is mounted for rotation about a horizontal axis below the lower end of the gate carrying frame. In construction, the drum comprises two circular side discs 22 located in parallel vertical planes and spaced from each other, having diametrically disposed partitions 23 between and connecting said disc sides. Two of such diametrically disposed partitions are used thus dividing the drum into four quadrant shaped compartments or chambers. As will hereafter be described, the drum is always stopped with one of the partitions vertically disposed and the other in a horizontal plane as shown in Fig. 1. Thus, when the spinach leaves or other materials are projected against the vertical stop plate 15, they drop into the front upper compartment of the drum, as shown in Fig. 1, but when the gate 5 is in its lower obstructing position, it is the rear upper compartment that receives such material.

Four pins 24 extend laterally in an outward direction from one side 22 of the drum. They are located 90 degrees apart and in the same planes with the partitions 23. Horizontal frame bars 25 extend between the front and rear posts 1 of the frame at each side thereof in a plane substantially coincident with the turning axis of the drum. The drum is mounted for rotation on the spaced sides of a U-shaped fork having a transverse rear bar 26 and spaced forwardly extending sides 27 and 28, one at the outer side of each side of said drum, with the ends of a shaft through the drum at its center rotatably mounted near the free forward ends of said sides 27 and 28. The sides of the fork toward their rear ends are mounted for rocking movement at 29 to rock about a horizontal axis, being carried by the frame bars 25. A rod 30 extends rearwardly from the rear bar 26 and near its free rear end carries adjustable weights 31 thereon. The drum mounting structure, therefore, has a limited tilting movement about the axis of the pivots 29. When the front upper compartment of the drum is empty, weights 31 lift the drum to an upper position, but when a sufficient weight of material has been delivered to said front compartment, its weight overcomes the weights at 31 and the drum tends to move bodily in a downward direction.

At the outer side of the side 22 of the drum which carries the pins 24, a disc 32 is secured from which four pins 33 extend outwardly, equally spaced from each other and radially aligned with the pins 24. A bracket 34 is mounted on the

side 27 of the drum fork support and is curved upwardly and forwardly, as shown in Fig. 1. Near its free forward end it carries a switch closing member 35 against which the pins 33 come in succession on rotation of the drum 1, moving the switch member 35 to control an electric circuit in which said switch is included, with each 90 degrees of rotation of turning of said drum for a hereafter described purpose. A second switch 36 (Fig. 1) is mounted on the main frame above the arm 27 forward of the pivots 29. The switch 36 is closed by engagement of the side 27 thereagainst when the drum is tilted down by the weight of the material in its front forward compartment.

As shown in Fig. 5, a bracket 37 is permanently secured to a rear transverse frame bar 3 disposed (in Fig. 1) a short distance above the tilting drum carrying frame. On bracket 37 a 20 solenoid winding 38 is mounted. The armature 39 extending below the winding 38 is pivotally connected at its lower end to the end of a lever 40 pivotally mounted between its ends on the bracket, the free end portion of the lever 40 extending over rod 30. The position of the lever 40 is controlled by energizing or deenergizing the solenoid 38. In one position it interposes a stop against the upward movement of the rod 30. Said rod is permitted a greater upward movement 25 when the lever is as shown in Fig. 5 than when the armature 39 is moved upwardly upon energizing the solenoid winding 38.

At the opposite side 22 of the drum a block 41 with rounded corners is connected (Fig. 4). It turns with the drum about the same horizontal axis of rotation. An arm 42 is pivotally mounted at its rear end on and at the upper side of the side 28 of the drum carrying fork, extending forwardly and upwardly therefrom. An adjustable screw 43 is mounted on and passes through the forward portion of the arm 42, at its lower end coming against the upper side of the side 28, and is normally moved in a downward direction by the spring 44. A pin 45 extends laterally and inward from the arm 42 over the edges of the block 41. Such structure as described interposes a brake upon the free rotation of the drum as the corners of said block come to said pin, and such braking action may be increased or diminished by the adjustment of the screw 43. When the pin is riding upon the rounded corners of the block 41, the braking action is greatest and midway between said corners, it is at a minimum or absent.

55 The spinach receiving drum is rotated (Fig. 4) by means of a pressure fluid cylinder 46, from the piston of which a rod 47 extends. On the rod a block 48 is secured which at the end edgacent the piston has a downwardly extending projection 49. At the other end a spring latch 50 is pivotally mounted having an inclined under side as shown.

On entrance of a pressure fluid, such as compressed air, at the inner end of the cylinder 46 rod 47 is moved inwardly. The dog 50 engaged 60 with a pin 24 gives a strong rotative impulse to the drum which under the momentum imparted is turned through a quarter of a circle in the direction indicated by the arrows in Fig. 4, so that the spinach or other material in the upper front compartment or chamber of the drum is dumped into a lower positioned hopper 51 (Fig. 1). The drum is stopped after it is moved through one-quarter of a complete rotation by the next succeeding pin 24 riding under the inclined edge of 65 latch 50 and coming against the projection 49.

rod 47 by such time having been returned to its initial position. Immediately preceding the engagement of the next succeeding pin with the projection 49 the braking or retarding structure which has been described exerts its greater force, pin 45 riding upon a corner of the square block 41. Likewise such braking or retarding is at a minimum during the earlier parts of the drum rotation.

A horizontal platform 52 is mounted on and carried by the machine frame a distance below hopper 51 and is narrowed in width at its front side and extended a distance in front of the frame as indicated at 52a (Fig. 9). The hopper 51 is open at its lower end and so that the vegetable material, such as spinach or the like, passes through it and within the confines of U-shaped presser member having a curved inner end 53 and parallel vertical spaced sides 54, (Figs. 6 and 11). Said presser member is mounted for outward and inward movement on the platform 52, the lower edges of the sides 54 being outwardly flanged and guided underneath spaced parallel guide bars 55 secured at the upper side of the platform and extending at their front ends to the outer edge of the narrowed platform portion 52a. Near the front edge of said narrow portion 52a, a vertical curved plate 56 is fixedly secured in place the spaced sides 54 of the presser member being located one at each side edge of the member 56. Member 56 is located at the front of a circular hole 57 made through the portion 52a of the platform 52a. At the under side of the forward narrow portion 52a of the platform, and in line with the opening 57, a bag holding spout 53 is permanently secured (Fig. 1).

The presser member is reciprocated by the longitudinal movement of a piston rod 59 extending into the end of a cylinder 60 and connected to a piston therein (Figs. 1 and 6). Compressed air or other pressure fluid is alternately conducted to the opposite ends of the cylinder. The spinach or other similar food material which has been dumped upon the platform 52 within the walls of the presser member is compressed substantially, a cylindrical form on outward movement of the piston rod 59, and as thus compressed is located directly over the opening 57.

A cylinder 61 is mounted vertically at the front of the machine frame over said opening 57. A piston rod 62 extends outwardly from its lower end, and at the lower end of the rod a substantially circular head 63 is secured. On the downward movement of the rod 62 the compressed spinach is pushed downwardly through the spout 58 into a bag which is releasably secured at its upper open end around the spout. The reciprocation of the rod 62 is controlled by the alternate conduction of the compressed air to the upper and lower ends of the cylinder 61.

The releasable bag holding structure is shown in Figs. 8 and 9, located at the under side of the platform 52.

Two jaw carrying arms 64, equipped each at its front end with the gripping jaws 65 shaped to engage the spout 58, cross each other and are pivotally connected together at the cross at 66. The inner ends of the arms 64 are connected by a coiled tension spring 67 which when free to do so, moves the jaws 65 toward the delivery spout 58 and presses against its opposite sides, a bag the open upper end of which is telescoped upwardly around the delivery spout.

Toggle links 68 pivotally connected at their meeting ends have pivotal connections at their

outer end one to each of the inner ends of the arm 64. When they are in alignment with each other, or slightly off dead center toward the front, they maintain the jaws 65 spaced from the spout 58 whereby the upper end of a bag may be placed therearound. The pivot pin connecting the adjacent ends of the toggle arm 68 is guided in a longitudinal guide 69. A roller 70 is mounted on the pivot pin at the knuckle of the toggle. When the jaws 65 are at inner gripping position, as in Fig. 8, the release thereof and freeing of the bag with the spinach or other material which in compressed form has been delivered thereto is accomplished by the outward movement of a piston rod 71 extending from the front end of the cylinder 72 having compressed air or pressure fluid alternately delivered to its ends. Such movement of rod 71 forwardly straightens the toggle from the position shown in Fig. 8 to that in Fig. 9.

With the gripping jaws positioned as in Fig. 9 after a bag has been located over a spout 58 the toggle is broken by manually operated means. Such means or mechanism consists of a rod 73, having a head 74 to push against at its front end, and which carries an arm 75 the free end of which is disposed at the front in the path of movement of the roller 70. Rod 73 may be moved lengthwise through its supporting brackets 76 so as to push the roller 70 a short distance inwardly, whereupon the spring 67 will function, moving the jaws 65 to operative gripping position and clamping against a bag over the spout 58 and thereby hold it against accidental or undesired disconnection.

In Fig. 11 a diagram of the electric and pressure fluid circuits is shown. Pressure fluid carrying pipes 77 and 78 connect the upper end of the cylinder 14 and the outer end of the cylinder 46, and the lower end of said cylinder 14 and the inner end of cylinder 46, respectively. Pipe 79 connects the two pipes 77 and 78, interposed in the length of which is a movable valve which may be turned by moving an operating arm or handle 80 therefore, to direct compressed air passing to the valve housing through a pipe 81 to the upper and outer ends of cylinders 14 and 46 simultaneously, or, reversely, to the lower and inner ends thereof. The exhaust of the compressed air is outward through the pipe 82.

The valve actuating arm or handle 80 is moved clockwise when a solenoid winding 83 is energized by current flowing therethrough, moving the armature of the solenoid to the right (Fig. 11) and holding it as long as the current is not interrupted. Upon interruption of current through the solenoid winding the valve arm is moved in the opposite direction to reverse the flow of compressed air. It is to be understood that the armature is spring actuated for such movement.

One end of the solenoid winding is connected with a line or wire 84 leading to a source of electrical current. The opposite end of the winding is connected with the wire 85 which may be electrically connected, when contacts 86 are brought together, with the opposite wire 87 of the circuit. Upon breaking the circuit at the contact 86, reversal of the flow of compressed air takes place.

A relay 88 has a magnetic core which when energized moves the contact 86 connected with the wire 87 to the contact of the wire 85 as shown in Fig. 11. A second contact 90 is connected with the movable member of the relay being movable with the contact 86, said second contact at 90 having connection with a circuit wire 89 which

leads to one side of the switch 36. With the relay 88 a wire 91 leading to a source of electric current is shown. A second wire 92 from the other end of the relay winding has connected therewith a second contact with which the contact 90 is associated. Said wire 92 leads from the relay 88 to a timed relay 93, which has wires 94 and 95 therewith for the supply of electric current. The second wire 96 from the timed relay connects with one side of switch 35. The wire 97 leads to the opposite side of the switch 36. Wire 98 connected with wire 97 leads to the opposite side of the switch 35. From the timed relay 93, wires 100 and 101 lead to the end of solenoid winding 38 which operates the pivoted finger 40. An additional circuit wire 102 carrying current is connected with the wire 98 and, therefore, with one side of switch 35. The other wire 103 of such circuit leads to a second timed relay 105, the opposite wire 104 of which is connected with wire 96 and, therefore, with the other side of the switch 35. The current supplying wires for the timed relay 105 are at 106 and 107. One wire 108 from the opposed side of the timed relay 105 leads to and connects at one end of the solenoid winding 109, the other end of said winding being connected by wire 110 with a switch 111 the operation of open or closing of which is controlled by the movement of the spinach presser member, an edge of a side 54 thereof operating the switch. Said switch may be normally closed and, therefore, opened at the completion of the movement to compress the spinach into a cylindrical mass. The wire 112 leading from the opposite side of the switch is connected to the other side of the timed relay 105.

The presser member operating cylinder 60 has fluid pressure carrying pipe 113 and 114 leading to opposite ends thereof, which are connected with the valve housing, the control valve in which is operated by an arm 115 actuated in one direction by the movement of the armature of the solenoid 109 when current is passing through said solenoid, and in the opposite direction by the spring shown. The inlet and exhaust pipes 116 and 117 are associated with the valve housing in the usual manner.

The bag holding or clamping means has its pressure fluid supplied to cylinder 72 through pipes 118 or 119 alternately to opposite ends of said cylinder. The pipes connect with a valve housing, the valve of which is moved between two positions to control the direction of the flow of the air through an operating arm 120, said valve housing having inlet and exhaust pipes 121 and 122. The arm 123 is moved in one direction by the armature of a solenoid winding 123 while current is passing through said winding, a spring moving the armature in the opposite direction when the circuit is broken. A relay 124 is connected by the wires 125 with the ends of the solenoid winding 123. Said relay has associated therewith circuit wires leading to a source of electric current as shown at 126 and 127. The wire 127 leads to one side of a switch 128 in the path of movement of the head 53, the second wire 129 from the other side of the switch connecting with the relay 124.

The vertical cylinder 61 has compressed air carried to its upper and lower ends by the pipes 130 and 131, joined with a valve housing the valve within which is moved by turning the valve arm 132, the usual intake and exhaust pipes 133 and 134 for the pressure fluid being supplied for the compressed air circuit last described.

Movement of arm 132 in one direction is actuated by energizing of a solenoid winding 135 and in the opposite direction by a spring acting upon the solenoid armature. The ends of the solenoid winding are connected with a relay 137. The circuit wires 138 and 139 for supplying the relay with current, one of them, 139, as shown is connected with a switch 140 from which a wire 141 leads to the relay. Said switch 140 is also actuated by a side 54 of the spinach compressor member when a compression stroke reaches its extreme position of movement.

In the diagram shown in Fig. 11, the gate 8 is in upper position, which means that the compressed air is conducted to the upper end of cylinder 14 through the pipe 77 and to the outer end of the cylinder 46. Valve 80 is held by solenoid 33 which has current flowing through it in a position to cause the compressed air to pass through the pipe 77, and this flow of current through the solenoid winding 83 is continuous as long as the contacts 86 are together. The holding current through the relay at 88 is through the wires 91, the contacts at 90, wire 89 and wire 97 and through the switch 36. Upon a predetermined weight of the material, such as spinach being delivered to the front upper chamber or compartment of the drum, it is tilted in a downward direction about a pivot 29, and switch 36 is momentarily opened, whereupon the relay at 88 is deenergized and the contacts at 86 and 90 separated. Flow of current through the solenoid winding at 83 is interrupted and the spring actuated armature thereof moves valve arm 85 to reverse the flow of compressed air, which thereupon passes through the pipe 78 to the lower end of cylinder 14 and the inner end of cylinder 46. The gate 8 is moved to its down position and the rod 47 is moved outwardly, giving an impulse of rotation to the drum to move it through a quarter turn, as earlier described, dumping the drum compartment contents into the hopper below and moving the next succeeding upper compartment of the drum into receiving position.

During such rotative movement, a pin 33 closes the switch at 35, whereupon there is a current momentarily completed through the relay at 88 and the timed relay at 93 through the wires 91, 92, 96 and 98. This causes a reengagement of the contacts 86 and 90 and a momentary action of the lever 40 to return the drum to its normal operative position. The flow of compressed air through the pipe 78 is of short duration so that the reversal of compressed air flows by change of position of the valve arm 80 follows quickly after the gate 8 has been lowered and the drum given its one step of rotation through 90 degrees, the gate 8, and the rod 47 and the latch connected therewith returning to the initial position shown in Fig. 11. The circuit above described through the relay 88, the wire 91, the contact 90 and wires 89 and 97 and the switch 36 is a holding circuit and will energize the relay 88 until broken by the switch 38. The circuit 91—92—91—98, momentarily closed by the switch 35 as the drum rotates, momentarily energizes the relays 88 and 93, again closing the holding circuit above referred to, including the contacts 90 and 86, and causes the lever 40 to momentarily act to push the drum carrying fork back to operating position thereby closing the switch 36 and said holding circuit but this movement of the lever 40 is only momentary and it does not continue to hold the rod 30 depressed.

The structure thus described is for the control

of the rotative movement of the drum when the predetermined weight of material has been received in the front upper drum compartment, accompanied by a downward and very shortly after, an upward movement of the gate 8.

The closure of the switch at 35 during the turning movement of the drum closes a circuit through the wires 102, 103 and 104 through the timed relay 105, and in accordance with the interval of time by which the relay 105 is governed. The circuit including the wires 103 and 110 is closed energizing the solenoid 109 to move the valve arm 115 to change the flow of compressed air through the pipe 113 to the opposite pipe 114 connected with cylinder 60 and move the U-shape compressor 53—54 to compress the spinach into cylindrical form. It is to be understood that the switch 111 is normally closed. Such switch is opened by a side 54 of the compressor engaging therewith, thus breaking the circuit through the wires 110 and 112 whereupon the spring associated with the solenoid 109 acts to return the valve arm 115 to its original position, with pressure of air to the front end of cylinder 60 and a return of the compressor to its original position.

Compressed air to hold the head 63 in its upper position is directed through the pipe 131 to the lower end of the cylinder 61 with the valve arm 132, as shown, held in such position by the spring associated with the armature of the solenoid 135. The circuit through wires 138 and 139 is normally open being closed when the circuit 141 is closed on the forward extreme of movement of a side 54 of the compressor. Upon closing such circuit, the timed relay 137 acts after the proper interval to energize the solenoid 135 and swing the arm 132 to reverse the flow of compressed air to cylinder 41, whereupon the pushing head 63 is moved downwardly to force the cylindrical compressed mass of spinach into a bag, the upper end of which is located over the delivery spout 53. On such downward movement, the switch 128 which has been held open by the head 63 in its upper position, is closed, completing a circuit through the wires 127, 129 and 126 through the timed relay 124 with an operation of the valve controlled by the arm 120 to reverse the flow of compressed air from the front to the rear end of the cylinder 12, thereupon opening the bag clamping arms 64 so that the bag with the spinach therein is removable from the spout 53. On the return of the head 63 to upper position in closing the switch 128, the rod 71 returns to its initial position, but the toggle arms 68 remain in open position until released by manually operating the push rod 73 whereupon a new empty bag which has been placed upon the spout is gripped so that it will be held in place until a next succeeding compressed cylindrical mass of the spinach or other like vegetable material is delivered thereto.

With the construction described, the leaves or stalks of spinach in their loose form, are delivered to the conveyor and moved continuously toward and projected by the speed of the conveyor into the front compartment of the drum until a predetermined weight thereof has been delivered to cause a tilting of the drum in a downward direction by gravity, which thereupon starts the cycles of operation described in motion. At the instant that the drum tilts downward the gate 8 lowers so that no more spinach is delivered into the front compartment but it is deflected to fall into the next rear compartment and when the drum rotates the said next rear compartment moves to the front, the gate

rises and the spinach continues to flow into that same compartment which is now in front. The drum in the meantime has returned to its initial receiving position with the next succeeding compartment of the drum located to receive the spinach; and when a sufficient weight thereof is again delivered, all of the cycles described are repeated. The operation continues without interruption so long as delivery of spinach is continued.

The construction is sure and certain in operation, is very rapid in the packaging of large quantities of spinach in compressed form in a short period of time, and with each package of substantially the same weight. There is a very marked saving of time and of labor costs.

The invention is defined in the appended claims and is to be considered comprehensive of all forms of structure coming within their scope.

I claim:

1. In a machine of the class described, means for continuously conveying material in loosely separated condition and projecting it therefrom in a substantially horizontal direction, a drum having spaced sides and diametrically positioned partitions providing a plurality of compartments open at their outer ends, a vertical plate above the drum spaced from said conveyor means and disposed against which said loose material to be packaged is projected whereby said material is dropped by gravity into a preselected compartment of the drum, a tiltably mounted frame carrying the drum, said frame tilting to move the drum in a downwardly direction upon a predetermined weight of said material being delivered to said compartment, a substantially vertical gate slidably mounted over said drum in advance of said plate in the direction of movement of the material and spaced from the end of said conveyor means, means for lowering the gate, means for turning the drum, and means rendered operative by the downward movement of the drum for simultaneously actuating said lowering means for lowering said gate into the path of said projected material, and for actuating said drum turning means, combined with means for stopping the drum when it has turned through a predetermined arc.

2. In a machine of the class described, a supporting frame, a drum having a plurality of radially disposed compartments therein open at their outer ends, a tiltably support mounted to tilt about a horizontal axis, means for rotatably mounting the drum at one end of said tiltably support, conveyor means for projecting material in loose condition over the drum in a substantially horizontal plane, a vertical plate above the drum spaced from the conveyor means and in the path of the material for directing it by gravity to a selected compartment of the drum, said tiltably support for the drum upon accumulation of a predetermined weight of said material in said compartment tilting about its axis of movement to move the drum in a downward direction, means rendered effective by said tilting of said drum support for turning the drum through a preselected arc of movement, movable stop means mounted above the drum and spaced between the conveyor means and the vertical plate, and means controlled by the downward tilting of the drum carrying support for simultaneously moving said stop means into the path of movement of said material while the drum

11

is being turned, and thereafter moving it out of said path of material movement after the drum has been turned through its predetermined arc of movement, the material obstructed by said stop means when in the path of the material dropping by gravity into said next preceding compartment of the drum.

3. In a machine of the class described, a main frame, a tiltable support on said main frame, a drum having a plurality of outwardly opening compartments rotatably mounted on said tiltable support, means for continuously feeding loose material and projecting it in a substantially horizontal plane over said drum, fixed means in the path of said material for directing it into one of the compartments of the drum, a movable baffle movable into and out of the path of said material ahead of said fixed directing means and spaced from said feeding means, said movable baffle when in the path of said material acting to direct the material into another of said compartments in the drum, and means controlled by lowering of said drum under weight of material deposited therein to simultaneously move said movable baffle into the path of the material and to rotate the drum a part of a revolution.

4. In a machine of the class described, a horizontal conveyor for continuously conveying loose material to be packaged, and said conveyor projecting said material therefrom at an end thereof, a drum having radially disposed partitions and open at its outer side to provide a plurality of consecutive compartments around the drum, said conveyor end being disposed at one side of the drum, a vertical plate at the outer side of the drum farthest away from said conveyor against which the loose material is

12

projected from the conveyor for said material to drop by gravity in the compartment farthest away from the conveyor, a tiltably mounted frame tilting said drum in a downward direction upon a predetermined weight of said material being delivered to said compartment, a substantially vertical gate slidably mounted over the drum between the delivery end of the conveyor and said plate, means for lowering the gate, means for turning the drum, and means rendered operative by downward movement of the drum for simultaneously actuating said gate lowering means to lower said gate into the path of said projected material for delivering it into the compartment of the drum nearest the delivery end of the conveyor, and for actuating said drum turning means, combined with means for stopping the drum when it is turned through a predetermined arc and for simultaneously lifting said gate out of the path of movement of said projected material.

GEORGE L. McCARGAR.
